SASH LATCH

Lawrence H. Smith, Chicago, Ill., assignor to
Victor M. Langsett, Chicago, Ill., as trustee

Application June 20, 1947, Serial No. 755,856

2 Claims. (Cl. 20—54)

1

This application is a continuation-in-part of my prior application (now abandoned) for Sash latch, filed January 1, 1945, Serial No. 570,879.

This invention relates to a sash latch for horizontally slideable windows used on automobile buses.

Automobile buses are provided with horizontally slideable windows arranged in a frame which are so mounted with respect to the bus body that they may be pushed or kicked outwardly in cases of emergency. The windows in buses, due to vibration encountered in travel, are relatively hard to open and, when opened, normally tend to open wider than intended or to close by the vibration of the bus.

It is therefore the primary object of the present invention to provide a new and improved sash lock or catch for maintaining the bus sash in either closed position or open position, and to maintain the sash in such position.

Another important object of the invention resides in the provision of a flexible or resilient means applied to horizontally operating sash so as to maintain the sash either in its open or in its closed position, to prevent creeping of the sash caused by allowing for easy operation.

A further object of the invention consists in the provision of a new and improved resilient sash latch which may be manufactured at an extremely low cost, which may be applied readily either to new sash or existing sash, which is strong and durable in construction and which is not likely to get out of order.

Numerous other objects and advantages will be apparent throughout the progress of the specification which follows.

The accompanying drawings illustrate a selected embodiment of the invention with a modification thereof, and the views therein are as follows:

Fig. 1 is a detail elevational view of a part of a bus body, there being slideable sash provided therein, the sash lock being adapted for application to the sash;

Fig. 2 is a detailed cross section showing one form of the improved sash, frame and latch of this invention;

Fig. 3 is a detailed sectional view of one modification of this invention;

Fig. 4 is a longitudinal section showing another form of this invention arranged in operative position with respect to the window casing, parts being broken away for the sake of clearness; and

2

Fig. 5 is a cross section therethrough taken on the line 5—5 of Fig. 4.

The particular construction herein shown for the purpose of illustrating this invention comprises a bus body 1 having a casing frame 2 mounted and positioned in suitable parts or portions of the bus body. Horizontally sliding sash 3, 3 are mounted in a window sash frame 4 and are adapted for longitudinal slideable movement 10 in the frame. Each sash 3 may be slideable, or, if desired, one of the sash may be fixed and the other slideable relative thereto.

The window frame 4 comprises an angulated pre-fabricated member as clearly shown in Figs. 15 2, 3 and 5, and includes an inner U-shaped channel member 5 adapted to embrace a wall portion of the bus body 1, and is held thereto by means of a screw 6 passing through the casing frame 2 and a side 7 of the channel 5. An indented portion 8 is provided in the base portion of the channel 5.

A U-shaped channel 9 is formed upon each opposite side of the window frame 4 back-to-back with the channel 5, by means of an elongated lip 10 formed on one side of the outer U-shaped channel 5 and an inner elongated side 11 formed opposite thereto. Extending downward from the inner side 11 and in a modified continuation thereof and preferably formed integral therewith, is an elongated lip 12 extending the length of the window frame 4. This elongated lip 12 may be offset at 13, as shown in Fig. 2, or, if preferred, may be made a straight extension of the side 11. Carried upon the elongated lip 12 is a strip 14 having spaced detents or depressions 15 which extend transversely across the member 12, spaced at regular intervals along the length thereof. The elongated strip 14 is affixed to the member 12 by means of rivets 16 as shown in Fig. 2 or by welding or the like.

The window sash 3 comprises a frame 17 having a U-shaped member 18 into which a glass 19 or other transparent material is mounted by means of resilient material 20. A lip 21 extends completely across the top of the sash 17 and is positioned opposite the U-shaped member 18 as shown in Fig. 2. Resilient material 22 of any suitable composition forms a weather-tight seal between the frame 4, the sash 17 and the lip 21. The lower side of the window frame 17 and the sash frame 4 may be of any proper construction so as to permit slideable movement of the sash and at the same time make a weather-proof and water-tight connection between the sash frame 55 and the window frame.

It is to be understood that while the particular window frame and sash construction described in the preceding paragraph is designated as being in the upper section of the sash and frame, this construction could be provided also or equally as well in the lower section of the sash and frame, without departing from the spirit of this invention. Obviously, if such a transposition is made, the upper sections of the sash and frame will be suitably constructed so as to permit slidable movement of the sash, and at the same time, make a weather-proof and watertight connection between the sash and frame.

A sash latch 23 of the "bullet" type is provided in the sash frame 17 as shown in Fig. 2. A 15 spring 24, held in place by means of a screw 25, urges the bullet latch 23 outwardly against the detents 15 of the elongated strip 14 as shown in Fig. 2.

In the operation of this form of my invention, the window sash 3 may be slid horizontally by the application of just sufficient pressure to overcome the force exerted by the bullet latch 23 in the detent 15. However, there is sufficient friction between the bullet latch 23 and the detent 15 to hold the window in place against vibration of the bus.

It is here further pointed out that the compact assembly of the latch and detent strip lends itself to a simple, economical and compact assembly, which can be produced and fabricated very economically. Obviously this structure likewise provides ready accessibility to all of the parts subject to wear in case repairs are needed.

It is further pointed out that in providing the detent 15 transversely of the width of the strip 14, the sash frame 17 and the window frame 4 do not necessarily have to fit exactly in order to let the bullet latch 23 fit into the detent 15.

In the modification of this invention shown in Fig. 3, all of the parts are similar to those shown and described relative to Fig. 2 with the exception that elongated detents 26 are provided in the lip 12 proper, instead of being formed in a separate strip 14. Obviously, this construction would make the window frame lighter, and accordingly, may be more economical to produce.

In the modification of this invention shown in Figs. 4 and 5, there is a window frame 4 comprising an elongated pre-fabricated element which includes an inner U-shaped channel 27 which is affixed to the bus body 1 by means of a screw 6 connecting the sash frame 2 to a side 28 of the U-shaped channel 27. A depressed portion 29 is provided within the U-shaped channel 27 as shown in Fig. 5.

In this embodiment of the invention, an outer U-shaped channel 30 is provided opposite the inner U-shaped channel 27 and comprises an elongated lip 31 on one side of the U-channel 27 and a second elongated side 32 forming one side of the depressed portion 29 in the U-channel 30. Depending from and being a continuation of the side 32 is a lip 33 which may be off-set at 34, as shown in Fig. 5, or may be a direct continuation of the side 32 if desired. In this modification, the elongated lip 33 is provided to form a weather-strip for the window sash, which is also a function of the lip 12.

The window frame of Figs. 4 and 5, as in the embodiment of this invention shown in Fig. 2, comprises a U-shaped member 36 into which a glass or other transparent material 19 is mounted. A resilient material 20' for securing the glass 19' in fixed position within the frame 36

is provided as shown. A lip 37 is provided on the window sash 38 and is surrounded by resilient material 22' as shown.

Elongated shoulders 38 are provided within the U-channel 36, which shoulders 38 receive an elongated strip 39 provided with detents 40, as shown in Fig. 4. A small recess 41 is formed in the U-channel 36 to provide space to receive the back portions of the detents 40.

10 A sash latch 42 may be secured to a vertical bar or muntin 43 of the sash, being rigidly secured thereto in any desired manner, such as by means of screws or rivets 44. The latch 42 preferably is made in one piece from resilient material, such as spring bronze or the like, and comprises a straight part 45 which abuts a piece of the bar or muntin 43, as shown in Fig. 4. An upwardly extending part 46 of the latch is bent outwardly at an angle and terminates in the form of a hook or eye 47. The top of the member 47 is relatively round and smooth, as shown, for engagement with the detents 40 in the strip 39.

The recesses or indentations 40 are so spaced that a depression 48 will be engaged by the hook or eye 47 when the sash is in an open position, the indentations 40 being spaced so that certain definite degrees of window opening may be had. The sash latch 42 being made of flexible resilient material is adapted to slide across the indentations 40 when pressure is applied to the sash for opening or closing. However, the resiliency of the latch 42 is such that the sash may be retained in closed or adjusted open position when the eye 47 is in one of the recesses 40. The sash, therefore, may be slid to any position desired and then maintained in said position against vibration of the bus, by the resilient characteristics of the material from which the spring latch 42 is made.

40 Changes may be made in the form, construction and arrangement of the parts without departing from the spirit of this invention or sacrificing any of its advantages, and the right is hereby reserved to make all such changes as fairly fall within the scope of the following claims.

The invention is hereby claimed as follows:

1. In a sliding window structure adapted for use in a vehicle, the combination of a window frame having a channel shaped member with opposite sides, a slidable window sash having sliding engagement within the channel member in guiding relation thereto and with a clearance space between the channel member and the sash, said channel member having a flange carried thereby offset relative to one side thereof and extending in overlapping relation with the adjacent frame member of the sash and overlapping the clearance space between the sash and channel member, and an elongated strip carried by the flange and extending longitudinally thereof, said strip having longitudinally spaced indentations located in a side face thereof opposing an adjacent side face of the window sash arranged to form stops, and a spring-pressed plunger extending transversely through said adjacent frame member of the window sash in position for selective engagement with the indentations in the strip.
2. In a sliding window structure adapted for use in a vehicle, the combination of a window frame having a channel-shaped member with opposite sides, a slidable window sash having sliding engagement within the channel member in guiding relation thereto, said channel mem-

ber having a flange carried thereby extending in overlapping relation with the adjacent frame member of the sash, said flange being provided with spaced indentations located on the inside face of the flange facing the opposite side of the channel to form stops, and a spring-pressed plunger extending transversely through said adjacent frame member of the window sash in position for selective engagement with the indentations in the strip.
